UNITED STATES PATENT OFFICE.

REIDAR T. SHERWIN, OF NEW YORK, N. Y.

SAND BLOWER FOR AUTOMOBILES.

Application filed November 26, 1923. Serial No. 676,964.

To all whom it may concern:

Be it known that I, REIDAR T. SHERWIN, a citizen of the United States, and a resident of Jackson Heights, New York city, county of Queens, and State of New York, have invented certain new and useful Improvements in Sand Blowers for Automobiles, of which the following is a specification.

10 This invention relates to apparatus for use on automotive vehicles, for the purpose of delivering sand to the ground on the roadway in front of the rear wheels of the vehicle for the purpose of preventing skidding of the car.

15 The object of the present invention is to provide an apparatus of this character, under the instant control of the operator of the vehicle, that will cause the sand blast 20 to be forced on the ground in front of the rear wheels of the vehicle and which is effected by a blower or fan having suitable operating means under control of the driver of the car; and also in which arrangement 25 one of the pipes is extended upwardly to prevent escape of the sand when the blower is not in operation.

30 In the accompanying drawing showing one embodiment of my invention, Figure 1 is a partial plan view of the car chassis.

Fig. 2 is a perspective view showing the blower and the sand box indicating the electric system.

35 Fig. 3 is a side view enlarged of the blower, partly broken away to show the interior.

Fig. 4 is a front elevation of the blower, partly broken away to show the interior.

40 Fig. 5 shows the discharge pipe. In the drawing a car chassis is partly shown with the usual mechanism, including an electric battery 2 arranged on cross bars 3 of the frame, on which I also place a sand receptacle or box 4, that preferably has a 45 hopper shape bottom 5, connecting with an outlet pipe 6 to discharge the sand. This box may have a hinged lid 7, and also a wire section 8 at the top, so that only fine sand can be placed in the receptacle.

50 To the rear of this receptacle, I place a suction blower 10 in whose casing is arranged an electric motor at 11, with the motor shaft extending into the blower to rotate the fan blades 12 in the usual manner.

55 The fan will draw in air at the front opening 13, and discharge the same at an outlet

pipe 14 that is part of the casing 10 of the blower.

The pipe 6 from the receptacle extends into the front portion of the blower at 15 which is arranged a short distance below the bottom of the receptacle 4, so that the sand will tend to run by gravity into the lower part of the casing 10.

For the purpose of discharging this sand 65 on the ground in front of the rear wheels 16 and 17 of the car, I provide a pair of pipes 18 and 19 adapted to receive sand from the blower outlet and direct it in the path of the wheels as the vehicle proceeds. 70 But instead of connecting pipes 18 and 19 directly with the outlet I provide a pipe 14 that extends upwardly and rearwardly from the casing lower portion, as shown. At the upper end 21 of this pipe I connect the 75 discharge pipes 18 and 19, that extend outwardly and also downwardly as shown in Fig. 1. The purpose of this upwardly extending pipe 14 is to prevent the sand that would run into the bottom of the casing, 80 from running out of the discharge pipes when the blower is not in operation, and it is not desired to feed the sand. But as soon as the blower is started the sand will be easily driven up the pipes 14 then through 85 the discharge pipes 18 and 19, and will be drawn by suction from the box. By this arrangement of the upwardly extending pipe 14, no valve is required to prevent escape 90 of the sand, as would be necessary if the discharge extended downwardly from the inlet portion 15 of the blower.

To control the operation of the blower, I provide a circuit by wires 22 and 23 extending from the motor 11 through the battery 95 2, and thence to a switch or button 24 at a convenient place for the driver to operate, such as in the floor as indicated in Fig. 1.

In the operation of the device as set forth, the sand will flow by gravity through pipe 100 6 and the inlet 15 into the casing 10 at its lower portion, and since it can not escape because of the upward direction of the outlet portion 14, no sand will pass into the outlet delivery pipe or pipes. When the fan 105 is rotated from the motor or other source of power the blades will have direct engagement with the sand in the lower portion of the casing and will drive the sand up towards the outlet portion 14, at the same 110 time the fan will draw air in through the inlet 13 and force it through the outlet 14,

that will engage the sand at this portion and drive it through the outlets 14 and 21 as long as the fan is rotated. But when the fan is arrested no more sand will pass 5 through the outlet 14, but a portion will remain in the lower part of the casing ready for very quick action when the fan is again started. By this means the sand is first started in motion by its mechanical engagement with the fan blades, 10 before any considerable pressure of air is produced, and as soon as sufficient current of air passes through the outlet 14 the sand will be there ready for immediate action. 15 By this means a very quick delivery of sand is provided by both air pressure and blade action that is necessary when the driver finds that the car is about to skid, and it is not necessary to wait for a number of rotations of the fan to provide air pressure to 20 deliver the sand at the outlet.

If desired either of the discharge pipes 18 or 19 can be omitted and the sand delivered at one rear wheel only by a single pipe 25 32 as indicated in Fig. 6.

It will be understood that a device of this character is comparatively simple in its construction and arrangement and readily assembled on any motor vehicle. By simply 30 closing the switch the supply of sand is instantly placed on the ground in front and

at the sides of the rear wheels. When the driver reaches a dangerous condition of road where skidding is likely to happen, the sand is applied before the skidding takes place. Obviously, but a small quantity is needed and when the switch is released the motor will stop at once, so that the supply of sand is not wasted.

What I claim is:

A sanding device for vehicles comprising a sand receptacle, a substantially drum shaped blower casing having its lower part below the level of the receptacle bottom and provided with an air inlet, a blade rotatable 45 in the casing, means for operating the fan, a peripheral delivery extension on said casing extending outwardly and upwardly therefrom and provided with a lateral tubular terminal portion, a delivery pipe leading from the bottom of the receptacle to the casing and opening through a side wall thereof adjacent the lower end of the peripheral extension, and a tubular means extending from the tubular terminal to deliver sand to desired points, the blade fan having its blades arranged to intersect the path of sand flowing into the casing from the receptacle.

Signed at New York city, N. Y., this 17th 60 day of November, 1923.

REIDAR T. SHERWIN.
